UNITED STATES PATENT OFFICE.

EDWARD POWELL, OF NEW YORK, AND ALFRED S. MUNGER, OF WILLIAMS-BURG, N. Y.; SAID MUNGER ASSIGNOR TO SAID POWELL.

IMPROVEMENT IN MACHINES FOR ROLLING SPRINGS.

Specification forming part of Letters Patent No. 157,927, dated December 22, 1874; application filed April 7, 1874.

To all whom it may concern:

Be it known that we, EDWARD POWELL, of the city, county, and State of New York, and ALFRED S. MUNGER, of Williamsburg, in the county of Kings and State of New York, have invented a new and useful Machine and Process for Rolling Springs Automatically; and that the following is a full, clear, and exact description of the same, reference being had to the accompanying drawings, and to the letters of reference marked thereon, making a part of this specification.

This invention is a machine for forming spiral springs of irregular form; and the invention consists of a mechanism for guiding the wire in coiling it, as hereinafter set forth and claimed.

In the accompanying sheets of drawings, Figure 1 represents a plan or top view of our machine; Fig. 2, a side elevation of same; Fig. 3, a side view of a series of springs made on our machine.

Similar letters of reference indicate like parts in the several figures.

A represents the base or bed plate of our machine, affixed to which in any secure manner are pillow blocks or bearings B B¹ B² B³. Properly secured to, and resting within, the bearings of the pillow-blocks B are two shafts, b b. On one end of each of the shafts b are secured small gear-wheels c, so that gears of one wheel will mesh with the gears of the other. At the other ends of the shafts b are affixed feed-rolls C. These feed-rolls have a groove or channel, c', formed around them. Resting within a bearing, d, is a roller, e, with a prolongation, f, secured to it. Attached to the bearing d and a supporting-block, g, is a guide, h. The shank i of this guide is secured to the bearing d and supporting-block g by set-screws k, which pass through slots m. The guide h is immediately over the roller e, and is inclined slightly upward, (see Fig. 2,) and its front edge is angular, and it has its outer end formed with a slot or hook, n. Immediately under the hook n of the guide h is a roller, D. This roller is supported in a bearing, o, which forms part of a sliding shaft, E, this shaft working in a suitable bearing in the supporting-block p.

Supported in suitable bearings formed in the pillow-blocks B² B³ is a shaft, r. To one end of the shaft r is secured a gear-wheel, s, the gears of which mesh into the gears of an intermediate wheel, t, the gears of the wheel t meshing into the gears of one of the wheels c on the shafts b. To the other end of the shaft r is affixed an eccentric, F, and a cam, G, the cam G having a depression, v, formed on its side. Extending from the cam G to the shank i of the guide h is a lever, H, supported by a supporting-block, w, to which it is secured by a pivotal bolt, y. One end of the lever H engages with the shank i of the guide h by entering in a small notch therein. Immediately under the roller e is a guide-block, J. Secured to the shank i of the guide h and the supporting-block g is a spring, l; and attached to the bearing o or sliding rod E, and to the pillow-block B³, is a spring, j.

Having now described the construction of our machine, its operation is as follows: Rotary motion being imparted to the shafts b by belt around the driving-wheel K or otherwise, the same motion is imparted to the other shaft b by means of the gear-wheels c, and motion is also imparted to the gear-wheel t, and through it to the gear-wheel s, causing the shaft r to revolve. As the shafts b revolve the feed-wheels C revolve also, so that when a wire, L, is inserted between the feed-wheels C, and into the grooves c' of the same, the wire is drawn forward by the action of the rolls c, and forced between the roll e and guide-block J, under the base of the guide h, and diagonally across its inclined edge into the hook or slot n of the same. As the wire is thus drawn in, the eccentric F, revolving with the shaft r, is forced against the end of the sliding shaft E, and forces the periphery of the wheel D against the wire as it passes upward across the edge of the guide h, forcing the wire nearer to or farther from the roll e; or, in other words, shortening the curve of the wire as it passes between the roll e, guide-block J, and edge of the guide h, as the eccentric opposes its greatest leverage to the end of the sliding shaft E, and as the eccentric opposes its least leverage to the end of said sliding shaft, the shaft, with

the wheel D thereon, is drawn back by the recoil action of the spring *j*, so that the wheel D is alternately forced against and from the wire.

As the shaft *r* revolves, the cam *G* revolves also, and as the depression *v* of the same comes in contact with the end of the lever *H*, the end of the lever is forced inward to be again forced outward, as it is brought in contact with the other bearing-surface of the cam, causing the lever to oscillate slightly around the pivotal pin *y*. The lever *H* oscillating in this way, the end thereof which engages in the shank *i* of the guide *h*, imparts to said guide a horizontal reciprocating motion, by allowing the shank *i* to move or slide by reason of the slots *m* and the bolts *k*. This reciprocating motion of the shank *i* is facilitated by the action of the spring *l*, which alternately expands and contracts. This reciprocating motion of the guide *h* alternately draws in and forces out the wire *L* as it passes upward, confining the coils of wire at a greater or less distance apart, so that, as the wire is fed through the rolls and guide in the manner just described, it is necessarily forced from a straight line to a curve, and from one curve to a succession of curves, by the guide *h*, the slotted or hooked point of which confines the wire, and causes it to recurve, and at each recurve the reciprocating motion of the guide causes the wire alternately to curve in different planes, forming a spiral. And as the wheel *D* is moved against and from the wire by the action of the eccentric *F*, the curves are lengthened or shortened alternately, so that, as for instance, when the wire is first introduced between the rolls, and to the action of the guide, the eccentric opposes little or no pressure against the sliding shaft *E*, and consequently the wheel *D* is at its farthest point from the wheel *e*. The wire then, as it passes upward, has given to it curves of the largest radius, (forming one end of the spring,) and, as the eccentric *F* gradually bears with increased force against the sliding shaft *E*, the wheel *D* is moved gradually nearer to the wheel *e*, so that the curves or coils of wire are gradually shortened until the wheel *D* is forced to its nearest approach to the wheel *e*, when the curve of the wire will be at its least radius, (forming the center of the spring,) and

from this point, as the eccentric revolves, the sliding shaft *E* with the wheel *D* thereon, is gradually drawn backward from the wheel *e*, and in this way gradually permitting the curves of the wire to be increased until they have again assumed their largest diameter, (forming the other end of the spring,) and completing it. In this way the coils of wire are alternately increased and decreased as the wire is fed to the machine, forming a connected series of springs, as shown in Fig. 3. The springs may then be afterward cut apart, or a cutting device may be attached to separate each spring automatically as it is formed. To the roller *e* is secured a support, *f*, as before stated. This support is of the same diameter as the roller *e*, and in fact a prolongation of it, and is designed to support the first coil or spring as it is formed, as shown in Fig. 1, the support revolving freely on the roller *e*, as the spring is supported by it. After several of the springs are formed, they may be supported by a trough extending in line with the roller *e*.

Instead of the springs *j* and *l*, the reciprocating motion may be imparted to the sliding shaft *E* by eccentrics or cams, or in any other desirable way.

It is obvious that if the roller *e* is dispensed with, allowing the wheel *D* to impinge against the wire *L*, as soon as it shall have left the guide-rolls *C* on its way to the guide *h*, that the spirals may be formed with very nearly the same facility as with or by the use of the roller *e*.

Having thus described the construction and operation of our machine, what we claim as new, and desire to secure by Letters Patent, is—

1. A reciprocating guide, *h*, having the hook-shaped end for the purpose of regulating the coiling of the wire, substantially in the manner shown and described.
2. The guide *h*, in combination with lever *H* and cam *G*, substantially as and for the purpose specified.

EDWARD POWELL.
ALFRED S. MUNGER.
